UNITED STATES PATENT OFFICE.

EDWARD E. SULLIVAN, OF HAVERHILL, MASSACHUSETTS.

LAST.

1,125,601.

Specification of Letters Patent.

Patented Jan. 19, 1915.

Application filed September 24, 1913. Serial No. 791,518.

To all whom it may concern:

Be it known that I, EDWARD E. SULLIVAN, a citizen of the United States, residing at Haverhill, in the county of Essex and 5 State of Massachusetts, have invented an Improvement in Lasts, of which the following is a specification.

This invention relates to certain improvements in lasts, and particularly to lasts 10 which are made in two sections, and permit foreparts of different styles and shapes to be attached to the heel-part, in which no change in style needs to be made to correspond in the change of the forepart, said 15 lasts being known as "making lasts" or lasts on which shoes are made, as distinguished from followers or shaping lasts which are made in sections to permit their removal without placing strain on the shoes.

20 Prior to my invention various attempts have been made to produce making lasts with interchangeable foreparts, but, so far as I am aware, lasts of this character have not yet been practically employed, principally for the reason, I believe, that the manner of severance and connection so weakens 25 the last that it will not withstand the continued pounding and strain which is placed thereon during the beating-out operation, particularly when this operation is performed by hand, as is still the common practice in the manufacture of turned shoes.

The object of my invention is to provide 30 a sectional last in which different forms of foreparts may be employed, and which is of sufficient strength to withstand the strain of the beating-out operation, so that the last will be practically as durable as if it were not a sectional last, and the advantages of 35 being able to change the style of the last without making it necessary to manufacture a whole last may be secured. I accomplish these objects, in a general way, by so forming 40 the planes of severance between the sections, that the heel-part will form a direct support for the greater portion of the forepart which receives the blows during the 45 beating-out operation, without causing excessive strain on the connecting means.

50 The particular manner in which I preferably carry out the above object is illustrated in the accompanying drawing, in which,

Figure 1 is a side elevation, and Fig. 2 is a plan view of a last made according to 55 my invention. Fig. 3 is a longitudinal sec-

tional view on the line 3—3, of Fig. 2. Fig. 4 is a detail sectional view taken at the line 4—4, of Fig. 1. Fig. 5 is a detail bottom plan view of the heel-part section, and Fig. 6 is a detail top plan view of the fore-part section.

In the drawing the last is shown as comprising a heel-part section *a* and a fore-part section *b* separated by a plane of severance *x* which extends in approximate parallelism 65 with the bottom of the last, from points adjacent the lower, or front end of the instep portion of the last, rearwardly to points approximately midway of the shank, and a plane of severance *y* which extends from the 70 middle portion of the shank portion of the last, so that it intersects the other plane of severance at an oblique angle thereto. The last, as thus severed, provides the heel-part section with a forwardly projecting sup- 75 porting portion *a'*, and an upwardly extending abutting and retaining portion *a''*, when the last is in the usual inverted position in which it is held during the beating-out operation, as will be hereafter more fully ex- 80 plained.

To secure the sections together I provide a connecting screw *c*, which extends through a hole *a³* in the projecting portion of the heel-part section, from a point adjacent the 85 upper end of the instep portion of the last downwardly in a direction which leads to the ball-portion of the last. The screw *c* is threaded into a ribbed sleeve *d* which is rigidly secured in a hole or recess in the 90 fore-part portion formed in alignment with a hole *a³*, so that when the bolt *c* is screwed therein it will firmly clamp the fore-part section against the portion *a'* of the heel-part section. The lower end of the hole in 95 which the sleeve *d* is placed is closed by a wooden plug.

The fore-part portion is provided with one or more dowels *e*, which are fixed therein between the point where the bolt *c* enters the same and the rear end portion thereof. Said dowels extend nearly parallel to the plane of severance *y*, and project into the heel-part section a suitable distance, as shown.

100 The manner in which the two sections are connected and disconnected will be obvious.

When the last is used in inverted position during the beating-out operation, the strain 105 which will be placed on the fore-part sec-

tion, tending to break and injure the joint, will be in a large measure, received by the heel-part section, which will be firmly strapped onto the heel-part of the jack. The 5 action of the heel-section in thus supporting the fore-part section is largely due to the forwardly projecting support a' , which extends horizontally beneath the fore-part section, and provides a support therefor, be- 10 yond the ball-portion. During the beating-out operation the fore-part section is, of course, also supported on the toe rest of the jack. This rest is usually somewhat yielding, and in beating-out the extreme toe- 15 portion of the shoe, there is some tendency to throw the shank end of the fore-part section upward with relation to the heel-section, which action is resisted by the slight under cutting of the abutment a^2 . As the 20 projection a' is clamped firmly on the upper side of the fore-part section and the abutment a^2 is held in close engagement with the end thereof, said abutment also acts to resist forces tending to throw the shank portion 25 downward.

By placing the dowels closely adjacent the rear end of the fore-part section the dowels are enabled to strengthen the joint between said sections to the best advantage and as- 30 sist the screw in causing the fore-part section to be firmly wedged into the space be- 35 tween the portions a' and a^2 . The parts are thus securely held together and successfully resist the strain placed thereon by the beat- ing-out operation.

By extending the plane of severance to the middle portion of the shank from which point the shank curves downwardly according to the height of heel to be employed, the same 40 heel-part may be used with fore-parts adapt- ed for heels of widely varying heights, and by extending the plane of severance α to the lower or front end of the instep, the inter- 45 changeability of the heel-part will not be interfered with while the advantages hereinbefore referred to will be secured.

Copies of this patent may be obtained for five cents each, by addressing the "Commissioner of Patents, Washington, D. C."

I claim:—

1. A two-part making last for shoes con- 5 sisting of a fore-part and a heel-part sec- 10 tion each having two corresponding longi- 15 tudinal engaging faces, one extending from 20 the upper side of the last at points adjacent 25 the front end of the instep portion, rear- 30 wardly, and the other extending upwardly 35 from the shank portion to intersect the first, 40 to provide the heel-part section with a for- 45 wardly extending supporting portion for 50 the fore-part section, formed integrally 55 with the said heel-part section, and ar- 60 ranged to sustain the force of the leveling operation 65 on the fore-part section, and detachable connecting means for said sections extending 70 from one to the other through said longi- 75 tudinal faces, for clamping said correspond- 80 ing faces in firm engagement, substantially 85 as described.

2. A two-part making last for shoes con- 5 sisting of a fore-part and a heel-part sec- 10 tion each having two corresponding longi- 15 tudinal engaging faces, intersecting at an 20 acute angle, one extending from the upper 25 side of the last at points adjacent the front 30 end of the instep portion, rearwardly, and 35 the other extending upwardly from the 40 shank portion to intersect the first, to pro- 45 vide the heel-part section with a forwardly 50 extending supporting portion for the fore- 55 part section, formed integrally with the said 60 heel-part section, and arranged to sustain 65 the force of the leveling operation on the 70 fore-part section and detachable connecting 75 means for said sections extending from one 80 to the other through said longitudinal faces, 85 for clamping said corresponding faces in firm engagement, substantially as described.

In testimony whereof, I have signed my name to this specification, in the presence of two subscribing witnesses.

EDWARD E. SULLIVAN.
